UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL-STOVE.

1,369,030.

Specification of Letters Patent. Patented Feb. 22, 1921.

Application filed July 17, 1919. Serial No. 311,463.

To all whom it may concern:

Be it known that I, RUDOLPH HOFFMAN, a citizen of the United States, residing at Kankakee, in the county of Kankakee and 5 State of Illinois, have invented certain new and useful Improvements in Oil-Stoves, of which the following is a specification.

My invention relates to oil stoves of the type wherein an oil reservoir is supported 10 at one end of the stove frame and is adapted to supply fuel to a number of burners mounted beneath the stove top; and the invention has especial reference to the provision of an extension top or cover normally 15 positioned over the reservoir but swingable to one side to permit of the withdrawal of the reservoir upwardly from its support.

The object of the invention is to provide an advantageous method of mounting the 20 extension top with reference to the main top of the stove whereby to permit of the easy operation of the extension top from operative to inoperative position and vice versa.

In the drawings wherein I have illustrated a preferred embodiment of my invention, Figure 1 is a fragmentary side elevation of the end portion of the stove frame embodying the features of my invention. Fig. 2 is a fragmentary top plan view partly 30 in section showing the manner of mounting the extension top. Fig. 3 is an underside view of the same. Fig. 4 is a perspective view of the means for swingably supporting the extension top.

Referring to Fig. 1 of the drawings, 1 designates a stove frame having a top 2, 3 is an oil reservoir supported by means of a bracket 4 secured to the stove frame in operative association with an oil well 5 40 which leads by way of a pipe 6 to the stove burners (not shown). 7 designates the extension top for the reservoir.

The stove frame 1 and the means for supporting the reservoir 3 with reference to 45 the frame may be of any suitable construction and therefore need not be herein specifically described. The top 2 for the frame is also of the usual construction and provides a support for the extension top 7.

The extension top 7 may be made of a width somewhat less than the width of the stove top, and is mounted at one end of the stove top so as to swing in a horizontal plane into an inoperative position (dotted 50 lines Fig. 2) to one side of its operative

position, to permit of the withdrawal of the reservoir 3 from its supporting means.

The means for thus supporting the extension top 7 preferably comprises a bar 8 rigidly secured upon the underside of the 60 stove top 2 as by means of bolts 9 and projecting a substantial distance outwardly or forwardly from the main top. At its outer end said bar 8 has pivoted thereto as at 11, a hinge member 10, and to the latter the extension top is pivoted at 12. Said member 10 is substantially triangular in form (Fig. 4) and may be constructed from a single sheet of metal bent upon itself to form a segmental cavity or socket 13 adapted to 70 receive the bar 8. The pivotal connection 11 between the member 10 and bar 8 is located at the smaller or outer end of the member 10, and it will be seen that the member is free to swing relative to the bar 8 75 to the extent of the width of the socket 13. The pivotal connection 12 between the member 10 and the extension top 7 is located at the larger or inner end of the member 10 opposite the pivot 11 at the outer edge of 80 the socket 13. To form a lug to which the extension top may be pivoted, the ends of the sheet from which the member 10 is formed are brought together at this edge of the member in the form of a rib 14. As 85 shown in Fig. 3, the edge of this rib 14 is shaped so as to snugly engage with the down-turned side flange 7^a of the extension top, thus serving as a stop to limit the 90 swinging movement of the top 7.

In the operation of swinging the extension top into inoperative position, the member 10 is swung, in the initial movement of the top, on its pivot 11 from the position shown in full lines in Fig. 2, in which the 95 bar 8 engages with the inner wall of the socket 13, to the position shown in broken lines in said figure when the opposite or outer wall of the socket engages with the opposite edge of the bar 8. In such movement of the top 7 and member 10 relative to the bar 8, the pivot 12 for the top is swung through an arc described from the pivot 11 as a center and is carried outwardly and laterally from the stove top 2 100 105 a sufficient distance to permit of the free swinging movement of the extension top outwardly and transversely with reference to the top 2. The continued swinging movement of the top 7 upon its pivot 12 110

carries it to the position shown in broken lines in Fig. 2 to one side of its initial or operative position. In this position of the top 7, the reservoir 3 may be readily withdrawn upwardly from its support on the frame.

Near the edge of the extension top 7, opposite the hinging connection therefor, there may be provided a latch member 15 rigidly secured upon the underside of the extension top 7 as by means of bolts 16 and having a rearwardly projecting portion 17 adapted to enter a slot 18 formed in the end flange 2^a of the stove top 2. The portion 17 of the latch member 15 may be bent to form a hump 19 for preventing an accidental release of the extension top 7 from the top 2. When it is desired to swing the top 7 it is only necessary to lift slightly the end thereof carrying the latch member 15 to release the hump 19 from engagement with the edge of the slot 18, the hinging connection of the top being sufficiently flexible to permit of such lifting movement of the top 7.

It will be seen that I have produced in an oil stove, an extension top mounted in a very practical manner with reference to the main top. The construction is advantageous in that it involves few parts of substantial simplicity, and the operation of swinging the extension top from operative to inoperative position and vice versa requires a minimum expenditure of effort.

While I have herein illustrated and described the invention with considerable particularity, I desire to have it understood that in the interpretation of the appended claims they are not to be limited except as may be necessitated by the state of the prior art.

I claim as my invention:

1. An oil stove comprising, in combination, a frame, a reservoir mounted on one end of the frame and a top for the reservoir swingable in a horizontal plane to a position at one side of the frame to permit of the withdrawal of the reservoir.

2. In an oil stove, the combination with a frame and an oil reservoir supported at one end of the frame, a top for the reservoir having a pivotal connection with the frame, said connection comprising a pivot movable outwardly and laterally with reference to the frame.

3. In an oil stove, the combination with a frame and an oil reservoir supported at

one end of the frame, of an extension top for the reservoir, and means for swingably supporting said top comprising a member pivotally mounted at one end a substantial distance from the frame and having the extension top pivoted to its opposite end, the last mentioned pivot being swingable on an arc struck from the first mentioned pivot whereby to carry said top outwardly and laterally with reference to the frame.

4. In an oil stove, the combination of a stove top, an extension top, and means for swingably supporting the extension top to swing in a horizontal plane outwardly and laterally with reference to the stove top.

5. In an oil stove, the combination with a main top and an extension top, of means for swingably supporting the extension top comprising a triangularly shaped member having a socket therein, a part fixed to the main top projecting into said socket and pivoted to the outer end of said part whereby to permit said member to swing to a limited extent relative to said part, and said extension top being pivotally mounted on said member at its larger or inner end.

6. In an oil stove, the combination with a main top and an extension top, of means for swingably supporting the extension top to swing in a horizontal plane to one side of its normal or operative position, and a latch member on one top adapted to engage with the other top to releasably hold the extension top in such normal or operative position.

7. In an oil stove, the combination with a main top and an extension top, of means for swingably supporting the extension top so as to permit it to swing horizontally from a position with one edge abutting the end of the main top to a position at one side of its normal position, and vice versa, and means for releasably holding said extension top in its normal position.

8. In an oil stove, the combination with a frame and a reservoir supported at one end thereof, of an extension top forming a cover for said reservoir, means providing a movable pivot upon which said cover is adapted to swing horizontally from a position over said reservoir in a direction outwardly as well as laterally from the frame, and means for releasably holding the cover in its operative position.

In testimony whereof, I have hereunto set my hand.

RUDOLPH HOFFMAN.
